[57] CLAIM

The ornamental design for a pacifier holder, as shown and described.

DESCRIPTION

FIG. 1 is a perspective view of a pacifier holder, showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a perspective view of a second embodiment of the pacifier holder, all undisclosed portions being identical to that shown in FIGS. 2-7; with the only difference residing in the omission of the handle.

FIG. 1

FIG. 2

FIG. 3

FIG. 4

FIG. 5

FIG. 6

FIG. 7

FIG. 8
